CIRCUIT CONTROLLER

Wilhelm Höpp, Heiligensee, Germany, assignor
to General Electric Company, a corporation of
New York

Application April 5, 1930, Serial No. 441,982, and
in Germany July 11, 1929

15 Claims. (Cl. 200—88)

My invention relates to switches and has for an object the provision of an improved switch with thermal release which has large switching capacity and high switching speed. Though my invention is suitable for a wide variety of application it is particularly suitable as a protective switch for arc rectifiers or the like.

In the case of rectifiers with glass envelopes, protection against overload is ordinarily obtained by means of explosion-proof safety fuses, because such devices provide the variable permissible switching time which is in agreement with the heating of the anode lead-in caused by varying overloads. With the customary overload current switch and even a quick acting switch, the desired protection can not be obtained because every mechanically operated switch has a definite operating time of its own which is determined by the inertia of its moving parts. In order to increase the disconnecting speed, it is necessary to reduce the mass of the movable parts of the switch to a minimum.

In the case of thermally released switches, quick action is most readily obtained by direct heating of the thermal element, since indirect heating causes a delayed release. However, for heavy current service ordinarily a special cutout switch is required which is controlled mechanically or electrically by a thermal time relay. In this case, the particular time required for operation of the excess current switch depends on the heating of the time element as well as the retarded operation of the cutout switch, so that in the case of arc rectifiers, considerable damage may occur before the endangered circuit is interrupted.

Compared with this, the improved switch embodying the present invention has a very short opening time and at the same time large current controlling capacity. According to the preferred form of the invention the movable switch actuating part consists of a bi-metallic thermal element formed as the main switch lever and traversed by the main current. The bi-metallic element carries the movable contact at its free end. The thermal element itself is thus used directly for effecting the interruption of the current. In this case the relatively high contact temperature occurring due to the heating of the bimetallic element is overcome by the use of non-oxidizing contact parts. Moreover, that the welding together of the interrupting contacts is prevented to a very considerable degree by means of an overcenter spring mechanism providing a sufficient contact pressure during the disconnecting

movement, and which also insures the immediate separation of the contacts with great switching speed. The further details of the invention may be best explained by means of the constructional example represented in the drawing.

In the accompanying drawing Fig. 1 is a side view partly in section of a circuit controller embodying the present invention; Fig. 2 is a chart showing the variations in the operating forces occurring during operation of the circuit controller; Fig. 3 is an enlarged view showing a modification of the operating electromagnet for the switch; Fig. 4 is a view partly in section showing the detailed construction of the electromagnet armature and the thermal element; Fig. 5 is a top view showing the detailed construction of the contact mechanism and Fig. 6 shows a modification of the switch operating electromagnet structure.

As shown in Fig. 1 the bi-metallic strip 1 traversed by the main current is firmly secured at its lower end, and at its upper end carries the main switch contact 2, whose mass is small. The result of this is that the temperature of the bimetallic element is transferred to the main contact with hardly any diminution. Since for the safe protection of electric lines and machines the operating temperature required for the bimetallic strip fluctuates within the limits of 100–200° C., the oxidation temperature for customary copper contacts is considerably exceeded. In order to overcome this difficulty, the main movable contact or the cooperating contact piece is provided with a silver insertion 3 at that point at which the contacts touch one another in the circuit closing position. The cooperating contact 4, moreover, is not rigid, but is arranged so as to be yielding and is limited in its switching path by means of a stop 5. In order to keep the mass of the cooperating contact small, the current is conducted to the same through a resilient band 6. The opening movement of the main contact 2 is also limited by a fixed stop 7. The operating force of the cooperating contact spring 6 is proportioned to that of the bi-metallic strip 1. In order to effect an instantaneous disconnection a powerful overcenter spring 8 is arranged so that on the opposite sides of the dead center, or critical position, it exerts a greatly increasing additional force on the contact 2 to either to close or to open the same.

The operation of the forces of the mechanical system described, according to Fig. 1, can be seen from the diagram of Fig. 2. The characteristic lines, that is to say, the curves of the forces ex-

erted by the resilient contact 1 and of the resilient cooperating contact 4, are approximately straight lines. The characteristic of the force occasioned by the tension of the overcenter spring 8 is also practically a straight line in the case of its displacement beyond the dead center position. The position and direction of these characteristic lines are so selected according to the invention that the desired quick operation is brought about in the following manner.

The closed position of the contacts indicated in Fig. 1 is selected in the diagram as the zero point, the movement of the switch elements being represented along the abscissas and the forces on the switch elements by the ordinates. The closing force acting to the left in Fig. 1 is reckoned as positive and the opening force as negative.

The force at the contacts 2 and 4, due to the displacement of the thermal element, is represented by the line Br at normal temperature, but it will be seen that this force is zero in the closed position. If the temperature of the thermal element is increased above the normal temperature by a predetermined amount the force at the contacts will be represented by a straight line which is parallel to the line Br and displaced from it a predetermined amount. For example, assuming that the thermal element is unrestrained, the force at the contacts will be represented by the line Bg and in the diagram this line corresponds to the temperature required to open the contacts. Upon reaching the releasing temperature, however, the characteristic line of the bimetallic strip is displaced by the amount Bgo which represents the thermal expansion due to the heating produced by the load.

The characteristic line Z of the spring 8 (considered with respect to the force exerted on contact 2) always cuts the zero force line in the dead center of the path of movement of contact 2 which distance is represented by the distance St along the abscissa axis. In the zero position the force of the spring has the initial value represented by the ordinate Zo . Finally there is further the characteristic line K of the counter contact 4. In the closed position the force on the contact 4 is represented by the ordinate $-Ko$ (minus because it represents an opening force which has been plotted above the abscissa). As shown, this force diminishes somewhat before the contact 4 is arrested by the stop 5. The force at the distance Sk drops to zero. In order to maintain the switch in the closed position, Zo must of course be greater than the initial force Ko of the counter contact. As shown, the contact pressure is represented by the difference between the forces Zo and Ko .

With increased heating of the bimetallic element a force is developed tending to open the contacts and counteracting the residual force due to Z and K . When the force due to the thermal strip is such as that represented by the line Bg the net force on the contact element is zero and a very slight further increase will produce a net force tending to move the contact element to the right. The contacts will not separate yet due to the counter contact spring. The shaded area includes the forces at any point in the movement tending to accelerate the contact element. After a deflection Sk the contact element has attained high speed, but now the counter contact is suddenly checked by part 5. The inertia of contact 2 and associated parts causes it to continue to move and open the contacts suddenly. Moreover, the over-center spring also tends to continue the

motion. The contacts are opened a distance So , large enough to interrupt the current but kept as small as possible to reduce stresses in the bimetallic element as much as possible.

The overload switch fulfills the further requirement that when the bi-metallic strip cools no further automatic reclosure of the switch takes place. If the reclosure of the switch is desired, it can be accomplished without difficulty. For example, if So is made larger than a certain amount, the force of the bimetal tending to close the contacts (when cool) is less than that of the overcenter spring tending to keep the contacts open. This arrangement would be used when it is desired to have the switch remain open after being tripped. If automatic closing is desired, So is made smaller so that $Z-Br$ (representing the net force on the contacts) has a positive value tending to close the contacts. The cycle for the heating and the cooling of the thermal element is indicated by the plotted arrows.

The present construction requires only a small operating force in order to reclose the switch. Further, the entire system can be arranged practically without friction due to the absence of all complicated intermediate members, such as levers, pawls and rods. Thus the necessary forces for automatic operation are also small when the switch is to be reclosed or opened independently of the bimetallic strip. The new switch therefore is particularly adapted for remote operation, since its operating magnets may be exceptionally small.

It can be seen from the diagram that the conditions are fully illustrated for the special case mentioned. The variation of the value of the current required for automatic operation of the switch can be obtained in different ways, for example, by varying one or the other constant of the system. For convenient calibration a variation of the spring constants is desirable. The cooperating contact 4, for example, can have an additional spring 9, arranged so that the characteristic line results from the combined effect of the two springs 6 and 9. In addition to varying the pressure by tensioning or untensioning the spring 9, its constant can be adjusted by varying the number of turns. The spring constant of the over-center spring 8 can be conveniently regulated by means of an adjusting nut 10. Accordingly, as its force is varied the position of its characteristic curve Z is varied, since the latter must always pass through the dead center point St .

In the case of heavy short-circuits the temperature of the bi-metallic strip increases in the same manner as in the case of a safety fuse. Since there is no time for conducting away the heat on a sudden overload, the electric energy causes a quick rise in the temperature of the thermal element, whereby the expansion takes place very quickly. To open the switch it is only required to accelerate the small additional mass of the contact piece 2 and of the spring 8 which, as I have stated, is small compared with the masses in the customary switches and even quick-acting switches. Since the cooperating contact 4 is also burdened with a mass, in the case of a predetermined, high short-circuit current strength, this might not be able to follow the contact 2 with the same speed. Therefore, to facilitate acceleration of the masses, a thin iron sheet 11 is arranged behind the counter contact spring 6 which oscillates in front of the poles.

12 of the main current magnet 13 as a magnet armature. In the case of switches for small current strengths, it will be understood that the resilient current conducting band 6 may consist 5 of a magnetizable material, for example, steel, so that a special armature 11 is unnecessary.

The blow-out magnet 13 with coil 14 is used as main current magnet according to the invention. For obtaining a large switching capacity, contrary to the customary arrangement on excess 10 current switchboards, this is not arranged above or behind the main contacts, but in front of and somewhat below the same. A stationary auxiliary electrode 15 extends over the blow-out coil 14 and down the front side of the switch, so that the interruption arc can extend on the front switch surface entirely free and unhindered. At 15 both sides special pole horns 16 are provided, which are bent somewhat at right angles, and which produce the necessary blow-out field in front of the switch as well as over the same. In this arrangement the space surrounding the switch is better utilized than was hitherto the case, which is of special importance for completely encased switches. By means of the electrode 15 extending down in front, the entire switch is more effectively enclosed and at the same time better protected against mechanical damage.

30 A further innovation consists in the feature that the cooperating contact 4 which is suitably embedded in a U-shaped recess, is covered almost completely by insulating material. Only the upper part of the contact which is located in the blow-out field is exposed. In this way the switch is protected to considerable degree against the injurious effect of the arc gases in the case of disconnection through short-circuit, against re-ignition, and against interpole sparking. The blow-out arrangement is not built together with the contact, but is located at the front part of the switch. In the open position of the switch, no voltage difference exists between the contact and the blow-out poles. The front pole of the switch, 40 with the construction described, can without difficulty be entirely covered with insulating plates 17 since the operating mechanism and the connection for the individual switch poles (cross-bar 31 in Fig. 4) are located at the lowest end at the 45 greatest distance from the arc.

The total switching time of a switch, as is known, is made up from its own time and the duration of the arc. In order to avoid excessive heating of the thermal element 1 while the arc 55 lasts, the stationary horn 15 extends over the contact 2, so that after the occurrence of the arc it is led over on to the horn 15 in the shortest time. This arrangement, in this case serves the special 60 purpose of preventing excessive heating of the bimetallic element and thus shortens the time interval which is necessary before the reclosing of the switch can be accomplished.

As explained by means of the diagram Fig. 2, an automatic reclosing of the switch can be effected after the cooling of the bimetallic element by an appropriate adjustment of the spring constants. In order to be able to effect a reclosure before the cooling occurs, the dead or critical 70 point position of the rocking lever 1 can be varied. For this purpose the lower suspension point of the rocking spring 8 is mounted in a swing 21 which, as more clearly shown in Fig. 3, is rotatable about the point 25 against the effect of a stop 18 which 75 is yielding in the switch closing direction and

which is pressed into its end position, by the spring 19.

To operate the switch by hand only a small motion of the fixed end of the over-center spring is required. This can be shown in the diagram as a displacement of the line Z to the left or right. If Z is displaced a distance S_a to the left the force Z_o becomes equal to K_o and a position of unstable equilibrium ensues and the switch opens. If the switch is closed and Z is displaced to the right a distance S_e the force of the over-center spring is reduced to equal the force of the bimetallic element and the switch snaps closed.

80 If the switch is to be remotely operated then the swing 21 is formed as a magnet armature. At either side of this swing is arranged the closing and opening magnets 22 and 23 respectively.

85 A particularly effective remote release is obtained for the reason that the torque originating from the tilting spring 8 in the closing direction is partly or entirely balanced by an auxiliary force, for example by the springs 24. This arrangement has no influence on the contact pressure but to effect the opening of the switch only a small movement of swing 21 is required. If 100 the swinging armature 21 is further mounted on leaf springs 25 like a clock pendulum, so as to be free from friction, the sensitiveness can be increased to an extraordinary degree. This is of 105 great importance since it often is desirable that the switch be controlled by means of an auxiliary coil sensitive to faults other than overload.

90 The arrangement of an auxiliary magnet armature 11 Fig. 1 on the counter contact 4 already described above gives without difficulty the un retarded release in the case of excess current. This is accomplished because the contact path S_k , as can be seen in the diagram, is greater than the section of the path S_t which extends only to the dead center position. If the oscillating armature 110 21 has time to fall into the switch opening position before the interruption arc has been extinguished, then the switch opening operation is ensured. If however the arc breaks, say, as a 115 result of the existing counter E. M. F., then the contact 2 springs back into the switch closing position since the temperature of the bi-metallic strip 1 has not yet reached the releasing temperature. This kind of release is found to be particularly effective for very high short-circuit currents. However an additional overload release 120 independent of the heating is desirable. Therefore on the blow-out magnet 13 additional pole pieces 27 are arranged which extend as far as the oscillating armature 21 and magnetize the 125 latter independently of the releasing coil 23. Thus with the desired excess current the switch is moved positively into the disconnected open circuit position. The releasing current strength 130 can be adjusted by arranging a spring to exert a 135 counter force on the releasing armature 21 or by varying the gap between armature and magnet pole.

140 The described switch construction renders possible an extremely simple arrangement of a remote release, because the forces necessary for the operation are relatively small, and particularly because the movement of the operating mechanism is very small. In contra-distinction to this the known switches require complicated 145 lever mechanisms and pawl locking devices. In accordance with the present invention the means for insuring release free of the hand lever 29 consists in a simple movable coupling pawl 28 formed to function simultaneously as an armature 150

for the magnet pole 27 and as a mechanical connection between the hand lever 29 and the oscillating armature 21. Thus in the case of excess current the pawl 28 is influenced by the same magnet poles 27 which attract the oscillating armature 21.

In order to be able to maintain the switch as narrow as possible throughout its entire height, it is desirable to arrange the over center spring 8, 10 according to Fig. 4, between the divided bi-metallic strip. In like manner, the oscillating armature 21 may be divided at the upper part or provided with a notch 30 in order to provide room for the turns of the spring. The force of the tilting spring 15 8 is used, according to the invention, for securing the coupling member 31 in multi-polar switches. For this purpose the spring tension adjusting screws 10 of the individual switch poles are located below the cross-bar 31 and press the 20 latter against the individual oscillating armature 21.

In many cases it is desirable to increase the releasing current strength, for example during the starting of motors. In the present case this can 25 be very easily done by having the releasing armature 28 connected to the operating handle 29 so that the air gap between releasing armature 28 and pole 27 is enlarged by the switch closing movement of handle 29. After the completed 30 closure of the switch the handle 29 is moved back into the starting position by means of light spring 33 without thereby effecting a release of the switch. The stop 32 is then so arranged that in the closed position of the switch, the 35 member 28 is moved the maximum distance away from the magnetic poles 27 and thus increases the value of current required for releasing the switch.

An increase of the releasing current is also 40 brought about for the thermo element when the switch closing lever 29 is moved entirely into the end position against the pressure of the resilient stop 18, because Z_0 is increased thereby. In the case of immediate reclosure of the switch, after 45 the release has been effected by the thermal element, however, this method is only possible once because with the second switching-in the bi-metallic strip has become heated to a greater extent. This limitation, however, is desirable for the protection 50 of the switch as well as for the protection of the circuit.

A shunting of current from the main contact spring 6 is effected in the following manner: To obtain relatively great flexibility of the leaf spring 6, the same must be kept somewhat long and thin, 55 from which a high electrical resistance results. According to the invention now the non-oxidizing part 3 of the contact 2 is so arranged, for example, so extended, that it engages directly with the 60 grooved-shaped contact holder 34, as shown in Fig. 5. For currents which come below the limit current a large part of the current goes from the contact piece 3 direct through the contact holder 34 to the connecting bolt 35, and thus reduces perceptibly the currents passing through 65 spring 6. This is due to the fact that the ohmic resistance of the contact holder 34 is small compared with the resistance of the resilient spring 6. The contact surfaces on the contact holder 34 may be provided with a coating or a 70 layer of a non-oxidizing metal.

As I have already stated, a modern switch must be capable of general use. The applications of my inventions have already been described in 75 connection with remote controlled switches, with

multi-polar switches the switch being trip free of the operating handle.

With a slight alteration the switch can also be provided with an under-voltage release. For this purpose the auxiliary spring 24 is stressed beyond the point of equilibrium of the movable system, and in place of the switch closing coil, an undervoltage coil is provided. In this case the magnetism which originates from the undervoltage coil, acts in opposition to the force of the auxiliary spring 24. The value of the releasing voltage can be conveniently adjusted by varying the tension of the spring 24. In order to utilize the switch with undervoltage release for remote control, a series resistance is inserted in the energizing circuit of the holding magnet, which resistance is entirely or partly short-circuited by the remote control contact maker. The magnet thereby develops the necessary surplus pull with a large air-gap to close the switch. The resistance prevents overheating of the coil during the time the switch is closed. In the case of the hitherto known forms of overload switches with under-voltage release, such a remote control arrangement was out of the question, because of the energy requirements for closing the switch.

For certain switching purposes, remote control switches, in many cases, must be equipped with an automatic arrangement for deenergizing the 105 operating coils after the operation has been effected. The interrupter in this case entails special difficulties for the switch closing magnet, because the movement of the switch available for the movement of the coil deenergizing interrupter is mostly very limited. For example, in the case of latched switches, the interruption can only be effected at the very last moment, after the holding pawls, etc. have come into engagement. In order to make the coil deenergizing interrupter, 115 or the interlock contacts, safe in its action, special locking devices, quick-acting circuit arrangements, and complicated rod systems are necessary, which frequently give rise to faulty operations. Another difficulty is found in the 120 fact that the switch closing magnet consumes a large amount of energy which results in considerable arcing when the interlock contacts are opened.

In accordance with the present invention these 125 difficulties do not arise, since the forces necessary for the closing, as well as for the opening of the switch, are particularly small. The energy consumption of the switch closing coil is consequently very small; also by means of the present 130 construction, the described difficulty caused by the limited movement available only at the last moment, is avoided. In this case, the entire switching movement, from the dead center position as far as the final closing position is available for the interruption of the switch closing coil currents. Therefore, as indicated in Fig. 5, the interrupter contacts 38 and 39 for the switch closing coils can, without difficulty, be coupled with the counter contact 4. Thus in case the oscillating armature has fallen away, then the main contact automatically follows, and since the closing coil interrupter is moved direct by the latter, the interruption of the coil circuit is likewise guaranteed.

The interruption of the closing coil circuit by the interrupter contacts 38 and 39 can be made more certain by arranging the interruption arcs at such a point that a current of air, produced by the contact movement itself, is conducted to 135 140 145 150

the arc. The counter contact 4 is located, according to Fig. 5, in a U-shaped recess 34 which is tightly shut off above the contact by means of a short pole horn 5 (Fig. 1). At the lower 5 end and in front the recess is closed by means of insulating plates 36, 37 (Fig. 1). With the movement of the counter contact 4 a compression or a vacuum arises in the recess, since the resilient spring 6 operates in the recess like a piston (Fig. 5). The interruption contacts 38 and 39 are arranged laterally at this recess opposite openings 40 which lead to the interior of the recess. Thus a current of air is blown against the interruption contacts for the switch closing coil, or sucked up for the interruption contacts of the switch opening coil, whereby an easier extinction of the interruption arcs is brought about.

The switch can also be used as a contactor. 20 For this purpose it is only necessary to make the above-mentioned under-voltage arrangement and to leave out the series resistance. With the excitation of the switch closing coil 22 the contactor is closed and is automatically disconnected by the spring 24 upon the coil 22 becoming de-energized.

The described construction can also be advantageously used when a thermal quick-acting release is not desirable or is unnecessary. In this 30 case the bi-metallic strip 1 is replaced by the usual metal (steel or bronze). On account of the easy operation of the switch it is possible without difficulty to adjust the releasing current for low values. In this manner, that is to say, 35 without thermal release, the third or fourth pole of a multi-polar switch for example can be constructed.

The described magnet system can be used for protection against reverse current flow. Its operation is independent of voltage fluctuations within wide limits or of the magnitude of the current flow in the normal direction. For this purpose a current coil 41 (Fig. 6) is wound about the oscillating armature 21, while the shunt 45 coils 22, 23, are connected to the system or to a separate current source. The magnet system therefore acts as the polarized magnet, that is to say, with normal current flow, the armature is firmly attracted while with reverse current flow 50 the release takes place upon the reversal of the current. The character of the magnet system can be differently arranged by changing the air-gaps in the left or right magnet circuit.

What I claim as new and desire to secure by 55 Letters Patent of the United States, is:

1. In combination, a thermo-responsive movable switch member having means for insuring operation thereof with a snap action after movement of the switch member to a predetermined 60 critical position, a cooperating switch member biased for movement with said thermo-responsive switch member, and means for arresting the movement of said cooperating switch member as soon as the snap action movement of said first-mentioned switch member is initiated.

2. In combination, a movable thermo-responsive element, an over-center spring connected to said element, a movable switch contact mounted on said element, a cooperating switch contact biased for movement with said first contact, said 70 thermo-responsive element being arranged to control the operation of said over-center spring to operate said movable switch contact with a snap action to and from a closed circuit position 75 with said cooperating contact, and means for ar-

resting the movement of said cooperating switch contact as soon as said over-center spring initiates the snap action movement of said movable contact from a closed circuit position to an open circuit position.

80

3. An overload circuit breaker comprising a current conducting bimetallic element fixed at one end, a contact mounted upon the free end of said element, an over-center spring for operating said contact with a snap action between predetermined positions, said bimetallic element being arranged to operate said over-center spring from one over-center position to the other over-center position, a cooperating contact for engaging said first-mentioned contact, means for biasing said second contact for movement between predetermined positions so that when said bimetallic element operates the over-center spring said contacts remain in engagement until after said over-center spring initiates the opening of said contacts with said snap action.

90

4. An overload circuit breaker comprising a thermo-responsive movable switch member, a cooperating switch member biased for movement with the thermo-responsive switch member to a predetermined position, and an electromagnet energized in accordance with the current through the contacts for electromagnetically holding the contacts in engagement during movement thereof to said position.

105

5. In combination, a pair of cooperating movable switch members, a stop for limiting the movement of one of said members, and an electro-responsive means energized in accordance with the current through the switch members 110 for maintaining the same in engagement during the limited movement of said one member.

6. An overload circuit breaker comprising a current conducting bi-metallic element fixed at one end, a contact mounted upon the free end 115 of the element, a cooperating contact for engaging with the first contact when the temperature of the bi-metallic element is below a predetermined value and biased for movement with the first contact to a predetermined position upon 120 the heating of the bi-metallic element above said temperature, an over-center spring for biasing the first contact into engagement with said cooperating contact on one side of said position and out of engagement therewith on the other 125 side of said position, and means for controlling the action of said over-center spring to return said first contact into engagement with said cooperating contact.

130

7. An over-load circuit breaker comprising a current conducting bi-metallic element fixed at one end, a contact mounted upon the free end of the element, a cooperating contact for engaging with the first contact, an over-center spring for biasing the first contact into engagement with 135 said cooperating contact to conduct current to the bi-metallic element and out of engagement therewith upon a predetermined movement of the bi-metallic element due to heating, and means associated with said over-center spring for selectively biasing the first contact into and out of engagement with said cooperating contact upon the subsequent cooling of said bi-metallic element.

140

8. In combination, a thermal responsive element having one end fixed, an overcenter spring for biasing the free end of the element for movement on either side of a predetermined critical position depending upon the temperature of the element, and means including a movable member 145

150

for controlling the overcenter biasing spring to bias the free end of the thermal element from one side of said critical position to the other independently of the temperature of the element.

5 9. In combination, a thermal responsive element having an overcenter biasing spring and means including a movable member for controlling the overcenter biasing spring to operate the thermal element overcenter independently of the 80
10 temperature of the element.

10. In combination, a movable thermal responsive element having an overcenter biasing spring and electro-responsive means for controlling the overcenter biasing spring to operate the thermal element independently of the temperature 85
15 thereof.

11. In combination, a U-shaped thermal element having the ends thereof fixed, an overcenter spring having one end connected to the 20
20 thermal element and extending between the fixed ends thereof, and a movable member connected to the other end of the overcenter spring for controlling the biasing action of the spring on the thermal element.

25 12. An overload circuit breaker comprising a thermo-responsive movable switch member, an over-center biasing spring operatively associated with said member, means including a voltage responsive coil for controlling the over-center biasing spring to operate said movable member independently of the temperature of said thermo-responsive member. 100
30

13. In combination, a movable thermo-responsive element having an over-center biasing spring, 35
35 means for controlling the over-center biasing spring to operate the thermal element independently of the temperature thereof, comprising an

electromagnet provided with an armature, and energizing means associated with said armature operating said armature between predetermined positions so as to control the operation of said over-center biasing spring.

14. A circuit breaker comprising a current conducting bi-metallic element fixed at one end, a contact mounted upon the free end of said element, a cooperating contact for engaging said first contact, an over-center spring attached at one end to said bi-metallic element for biasing said first contact into and out of engagement with said cooperating contact upon a predetermined movement of said bi-metallic element, and a movable member to which the other end of said biasing spring is attached for operating said biasing spring over-center independently of the temperature of said element. 90

15. A circuit breaker comprising a current conducting bi-metallic element fixed at one end, a contact mounted upon the free end of said element, a cooperating contact for engaging said first contact, an over-center spring attached at one end to said bi-metallic element for biasing said first contact into engagement with said cooperating contact to conduct current to the bi-metallic element and out of engagement therewith upon a predetermined movement of said bi-metallic element, due to heating, and a movable member to which the outer end of said biasing spring is attached and electromagnetic means for operating said movable member in one direction or the other to control said over-center biasing spring so as to operate said element independently of the temperature thereof. 100
